A. BRUNNER

FUSE PLUG

Filed July 31, 1922.

INVENTOR.
ARTHUR BRUNNER

BY Bradley L. Benson
ATTORNEY.

UNITED STATES PATENT OFFICE.

ARTHUR BRUNNER, OF SAN FRANCISCO, CALIFORNIA.

FUSE PLUG.

Application filed July 31, 1922. Serial No. 578,686.

To all whom it may concern:

Be it known that ARTHUR BRUNNER, a citizen of the United States of America, residing at 1058 Ellis Street, San Francisco, 5 in the county of San Francisco and State of California, has invented certain new and useful Improvements in Fuse Plugs, of which the following is a specification.

The present invention is an improved 10 fuse plug.

The objects of the invention include;

(1) The provision of a fuse plug for electrical circuits such as interior house wiring, which is so constructed that when one fuse 15 has been destroyed by an overload of current others are available without the necessity of substituting another plug.

(2) The provision of a plug having a plurality of fuses radially disposed about the 20 center of the plug and insulated one from the other to prevent arcing or short circuiting of the current, and arranged in such a manner that the various fuses may be successively rotated to contact with a fixed 25 contact and thereby close a circuit.

(3) The production of a multiple fuse plug which will afford a maximum amount of service at a minimum cost.

In this specification and the annexed 30 drawings, the invention is illustrated in the form considered to be the best, but it is to be understood that the invention is not limited to such form, because it may be embodied in other forms, and it is also to 35 be understood that in and by the claim following the description it is desired to cover the invention in whatever form it may be embodied.

In the accompanying one sheet of drawings, Figure 1 is a vertical transverse section of my improved fuse plug;

Fig. 2 is a horizontal section taken on the line II—II of Fig. 1;

Fig. 3 is a bottom plan view of a porcelain sleeve member;

Fig. 4 is a top plan view of Fig. 1;

Fig. 5 is a plan view of a washer member;

Fig. 6 is a central cross section of Fig. 5;

Fig. 7 is a perspective view of a fuse clip or terminal.

Referring to the drawings, the numeral 1 indicates a cylindrical plug member of a suitable insulative material, such as porcelain.

The plug is enlarged at the closed end and

serrated as indicated at 2 to facilitate the rotation of the plug when it is desired to screw it into a socket. The plug 1 is provided with a central recess 3. A band 4 of sheet metal is helically threaded and one end of this band is embedded in or attached to the porcelain plug 1, while the opposite end protrudes to engage a lamp socket (not shown) in the usual manner.

A strip 6 of metal is soldered to the inner wall of the threaded metal member 4 and extended downwardly in the recess 3 to a point near the bottom.

At 7 I show a bushing member the exterior walls of which are serrated as shown at 8 to form longitudinal ribs 9 on the periphery of the bushing.

The inner wall of the bushing 7 is grooved longitudinally as shown at 11 to form channels for fuse wires 12.

These channels are closed as shown in Fig. 2 when a tubular member 13 is inserted in the bushing 7.

That end of bushing 7 which extends into the plug 1 is slotted radially as indicated at 14, Fig. 3.

The purpose of these slots is to engage and hold in radial arrangement spring clips 16 secured to the wires 12, Fig. 7.

In the drawings I have shown wires for fuses but, obviously, flat or other metal might be used.

It will be seen that in assembling my plug the wires 12 are laid in the grooves 11 with the flattened clips 16 in the several radial slots 14. The tubular member 13 is inserted and this closes grooves 11.

An insulating washer 17 covers the end of the member 13, and is of a diameter sufficient to engage the flat clip members 16 and prevent them from leaving the radial grooves 14.

At the end of member 13 remote from the plug 1, a washer 18 of conductive material covers the ends of the fuse wires 12 and these wires are pressed into engagement with a washer 21 of conductive material. This washer lies in a recess 22 of the outermost end of bushing 7.

The parts are securely held together by a screw 23 extending axially through the washers 17 and 18 and through the member 13. A nut 24 of conductive material holds the parts together and serves as a contact for the central terminal of a socket.

Current entering the plug through nut

24 passes through washer 18 and wire 12 to the contact 6 which is connected to the metal member 4.

Should the wire 12 be fused by an over-load, the bushing may be rotated until the next adjacent rib 9 is engaged by the arcuate contact strip 6. This operation may be repeated until all of the wires 12 are exhausted.

10 When all of the wires 12 are used, the parts may be dismembered and new ones inserted at small cost and very little effort.

I claim:—

A fuse plug comprising two concentric

cylindrical members of insulating material, 15 an electrical terminal centrally disposed with respect to the inner of said members, an electrical terminal peripherally disposed with respect to the outer of said members, a series of grooves between said members, 20 fusible conductors in said grooves, said conductors all electrically connected to one terminal of the plug, and each provided with a spring clip adapted to independently contact a conductor from the other terminal 25 of the plug when in register therefor.

In testimony whereof I affix my signature.

ARTHUR BRUNNER.
